(57) **CLAIM**

I claim the ornamental design for a pasturized bottle, as shown and described.

DESCRIPTION

FIG. 1 is a perspective view of the design for a pasturized bottle;

FIG. 2 is a left side view of the design of FIG. 1;

FIG. 3 is a right side view of the design of FIG. 1;

FIG. 4 is a top view of the design of FIG. 1; and,

FIG. 5 is a bottom view of the design of FIG. 1.

The portions of the drawings shown in broken lines are provided for illustrative purposes only and form no part of the claimed design.
